UNITED STATES PATENT OFFICE.

JAMES L. BROWN, OF ROCKPORT, KENTUCKY.

WARM-AIR ACCUMULATOR AND DISTRIBUTER.

1,220,723.

Specification of Letters Patent. Patented Mar. 27, 1917.

Application filed October 2, 1912. Serial No. 723,458.

To all whom it may concern:

Be it known that I, JAMES L. BROWN, a citizen of the United States, residing at Rockport, in the county of Ohio, State of Kentucky, have invented certain new and useful Improvements in Warm-Air Accumulators and Distributers; and I do hereby declare the following to be a full, clear, and exact description of the invention, such as will enable others skilled in the art to which it appertains to make and use the same.

This invention relates to warm air accumulators and distributers and particularly that type adapted for use in connection with open fireplaces.

The object of the invention resides in the provision of a device of the character referred to which will serve to maintain the passage of a current of air through a casing disposed in an open fireplace and discharge the same into the room or into a pipe for conveyance to a distant point after such air has been thoroughly heated.

With the above and other objects in view, the invention consists in the details of construction and in the arrangement and combination of parts to be hereinafter more fully described and particularly pointed out in the appended claim.

In describing the invention in detail, reference will be had to the accompanying drawings wherein like characters of reference denote corresponding parts in the several views, and in which—

Figure 1 is a front elevation of an open fire place having the invention associated therewith,

Fig. 2 a section on the line 2—2 of Fig. 1 with the device removed from the fireplace illustrated in Fig. 1,

Fig. 3 a section on the line 3—3 of Fig. 2,

Fig. 4 a section on the line 4—4 of Fig. 2, looking upward,

Fig. 5 a view of upper end of what is shown in Fig. 2 with the sliding closure removed, and

Fig. 6, a detail perspective view of the sliding closure.

Referring to the drawings A indicates an open fire place and B a grate disposed therein which is adapted to support the fire in the usual and well known manner.

The warm air accumulator and distributer is shown as comprising a U-shaped casing C which includes arms 10 and 11 and an

arm connecting portion 12. The interior of the arms 10 and 11 and the portion 12 all connect so as to form one continuous passage. Supported between the arms 10 and 11 is a hollow fire back 13, the upper end of which is disposed in spaced relation to the portion 12 of the casing B. The interior of the fire back 13 is connected to the interior of the arm 10 by means of vertically aligned openings 14 and 15 formed in said arm 10. Likewise the interior of the fire back 13 is connected with the interior of the arm 11 of the casing C by means of vertically aligned openings 16 and 17. The interior of the arm 10 is also in communication with the outside atmosphere through the medium of a pipe 18 mounted in the outer side of said arm and disposed below the opening 14. Likewise the interior of the arm 11 is in communication with the outside atmosphere through the medium of a pipe 19 mounted in the outer side of said arm. The front side of the portion 12 of the casing C is provided with an opening 20 which is adapted to be closed by the insertion of a sliding closure 21 into the interior of said portion 12. Another opening 22 is formed in the top wall of the portion 12 and has engaged therein one end of a pipe 23 by means of which warm air from the interior of the casing C may be conveyed to rooms located above that in which the fireplace A is disposed.

In the use of the device the same is placed in the fireplace A with the outer walls of the arms 10 and 11 in spaced relation to the adjacent walls of the fireplace. The grate B is then disposed in the fireplace A in the usual manner. During the burning of the fire upon the grate B cold air will enter from the outside of the room into the interior of the arms 10 and 11 through the pipes 18 and 19 respectively. The pure fresh air entering the interior of the arms 10 and 11 will in part pass to the interior of the fire back 13 through the openings 15 and 17 respectively where it will be efficiently heated. This heated air will then pass through the openings 14 and 16 to the upper portions of the interior of the arms 10 and 11 and thence to the interior of the portion 12 from where it will be discharged into the pipe 23. In the event it is desired to distribute the heated air into the room in which the fireplace A is disposed it is only necessary to remove the sliding closure

21 and close the pipe 23 when the heated air will be discharged through the opening 20 and will force the impure air to be carried off through the open fireplace.

5 What I claim is:—

In a device of the class described, a hollow casing formed to provide spaced parallel arm portions connected together at one end by a connecting portion and adapted 10 to be inserted within the fireplace in inverted position with the said arms in close proximity to and extending above the grate thereof, and with said connecting portion spaced above said grate, a hollow substantially shallow fireback connecting said arms throughout the major portion of their extent, the said fireback being spaced at its upper end downwardly from said connect-

ing portion to provide a duct communicating with the flue of said fireplace and extending at its lower end downwardly to terminate a slight distance above said grate, the upper and lower ends of said fireback being provided with openings communicating with the interior of said arms, a cold air 25 inlet pipe connected to each of the arms adjacent its lower end, and a hot air discharge pipe leading from the connecting portion.

In testimony whereof, I affix my signature, in presence of two witnesses.

JAMES L. BROWN.
